UNITED STATES PATENT OFFICE.

WILLIAM B. H. DOWSE, OF NEWTON, MASSACHUSETTS, ASSIGNOR TO THE CONSOLIDATED FASTENER COMPANY, OF PORTLAND, MAINE.

FASTENER.

SPECIFICATION forming part of Letters Patent No. 581,392, dated April 27, 1897.

Application filed August 20, 1896. Serial No. 603,299. (No model.)

To all whom it may concern:

Be it known that I, WILLIAM B. H. DOWSE, a citizen of the United States, residing at Newton, in the county of Middlesex and Commonwealth of Massachusetts, have invented a new and useful Improvement in Fasteners, of which the following is a full specification.

My invention relates to that class of separable fasteners consisting of a stud or male member and a socket or female member; and it consists of certain improvements in resilient socket members, hereinafter set forth in detail, reference being had to the accompanying drawings, wherein—

15 Figure 1 is a sectional view of the two parts of my socket member before they are riveted together on the material to which the fastener is attached. Fig. 2 is a horizontal section on the line 2 2, Fig. 1. Fig. 3 is a plan of the 20 under side of my socket member. Fig. 4 is a sectional view of my completed fastener attached to any material and showing the stud member (shown in elevation) snapped into the socket member. Fig. 5 is an enlarged 25 plan of my spring; and Fig. 6 is a vertical section of same on the line 6 6, Fig. 5.

My socket member S, Fig. 1, consists of two parts—a cap A and socket-piece E. The cap A consists of three parts—shell B, anvil C, 30 and centrally-perforated collet D, closed together at their outer edges, as shown. The socket-piece E consists of three parts—eyelet F, collet G, and spring H. The eyelet F has the attaching tubular eyelet f, the enlarged 35 stud-receiving chamber f', the spring-retaining chamber f'', and the horizontal flange f'', over which is closed the outer edge of the collet G.

The collet G is centrally perforated with 40 the hole g and confines within the chamber f'' the spring H. When the stud and socket members are together, as shown in Fig. 4, the head of the stud is within the chamber f', while its neck is engaged by the spring H, 45 the hole g in the collet G being of sufficient size to allow the stud to pass through easily.

My spring H, I make of a wire bent into the shape shown in Figs. 5 and 6, having six scallops arranged about a common center— 50 three long outwardly-convex centering-scal-

lops h h h, alternated by three short outwardly-concave scallops or stud-engaging points h' h' h'. The three long scallops h h h are so arranged that they form segments of a circumference of such a diameter that the 55 spring will lie loosely within the chamber f'' of the socket-piece E. The short scallops h' h' h' are so arranged that they will lie about the edge of the hole g in the collet G, projecting beyond its edge slightly, as shown in Fig. 60 3, so that as the stud member is pressed into the socket member these scallops or gripping-points h' h' h' will spring open to let the head through and afterward close about and engage with its neck, as shown in Fig. 4. Fur- 65 ther, I flatten the gripping-points h' h' h', as shown in Figs. 5 and 6, and also depress them slightly, leaving the centering-points round in cross-section and also in a higher plane than the gripping-points. Thus the spring 70 H is concave upward, and when closed into the eyelet-piece E it is in a measure flattened out, the centering-points bearing against the upper wall of the chamber f'' and the gripping-point sprung down against the edge of 75 the hole g.

I arrange my spring so that the joint or slit h'' comes at the end of one of the centering-scallops, as shown in Fig. 5, for by this means I find that the spring works more easily and 80 does not bind on the neck of the stud.

I claim—

1. In a stud-and-socket fastener, a socket-chamber provided with a scalloped-wire spring having the stud-engaging parts h' h' h' 85 projecting into the socket and the centering parts h h h, all arranged and operated substantially as described.

2. In a stud-and-socket fastener, a socket-chamber provided with a scalloped-wire 90 spring having the stud-engaging parts h' h' h' and the centering parts h h h, the said stud-engaging parts being flattened, substantially as described.

3. In a stud-and-socket fastener, a socket-chamber provided with a scalloped-wire 95 spring having the stud-engaging parts h' h' h' and the centering parts h h h, the said spring being provided with a slit h'', or discontinuous, substantially as described. 100

4. In a stud-and-socket fastener, a socket-chamber provided with a scalloped - wire spring having the stud-engaging parts $h' h' h'$ and the centering parts $h h h$, the said spring
5 being concaved so that the said gripping parts are in a lower plane than the said centering parts, substantially as described.

In witness whereof I have hereunto set my hand.

WM. B. H. DOWSE.
